BOOK

John V. Cavalero, Bloomfield, N. J.

Application March 24, 1934, Serial No. 717,136

3 Claims. (Cl. 281—36)

My invention relates to a book and particularly the binding and cover, and has for its objects:

To provide a durable cover and binding for hand books, prayer books and the like.

5 To provide a cover which may be kept clean and neat in appearance even though subjected to unusual wear and handling.

10 To provide a cover re-inforced with metal, pads and a substantial binding securing the cover to the book.

To provide a book and cover which protects the pages from being wrinkled and frayed at the edges.

15 I accomplish these and other objects by the construction herein described and shown in the accompanying drawing forming a part hereof, in which:

20 Fig. 1 is an end elevation showing a part of the cover and binding broken away to show the construction.

Fig. 2 is a view of my book showing the construction of the cover and binding.

Fig. 3 is a fragmentary view of the plies of the cover and the shape of the parts at the corners.

25 Fig. 4 is an enlarged fragmentary view of the parts of the cover showing how the cover is secured to the binding.

Similar reference characters refer to similar parts throughout the several views of the accompanying drawing.

30 The leaves (1) and flyleaves (2) and (3) are secured by adhesive to the fabric back (4). Said fabric back (4) is also secured between the part of the fly leaf finishing the inner face (5) of the cover (6). The card board inner resilient pad (7) as well as the cover (6) are prepared with glue or the like, said cover being roughened for and suited to adhere to said fabric back (4) as well as the facing (5) which is glued over said fabric which is thus secured between the resilient pad, cover and said facing, which is integral and a part of each flyleaf (2) or (3).

35 Clamped between the pad (7) and metal re-inforcing and stiffening member (8) are the under cover (9) and the transparent cellulose outer facing (10) which covers the picture or decorative facing (11) between the under cover (9) and the outer cover (10). Under said parts (9) (10) and (11) are the resilient member (12) and soft pad (13). A cellulose curved back facing (14) is provided to cover the fabric back (4).

40 The cover comprising the various parts, due to the shape and to the transparent cellulose facing is easily kept clean, protects the ornamental or decorative facing (11), all of which is of particu-

lar importance when the cover is white or of light tints, which, without a transparent covering would be quickly soiled.

5 The metal member (8) holds the shape of the cover and forms a base for the other parts which are firmly held by the edges of the metal member all of which are turned under with said metal member including the parts (9) and (10) and thus clamped between the metal member and the resilient pad (7) which lies between the turned over edges of the metal member and its body. The fabric back (4) is finished by the opaque facing (14) which may be white or colored, to match the decorative facing (11) or under cover (9).

10 The metal member (8) it will be seen, is so padded and covered that although in its strength and stiffness it does not have the cold, hard feeling to the touch of being metal, the cover is firmly secured to the binding and withstands great

15 wear and prolonged use, protecting both the binding and the leaves of the book as well as firmly holding all of the parts of the cover together by means of the four edges which are turned over with the metal member (8) which thus clamps all

20 of the several layers as well as the fabric back (4) under its turned over edges. The softer parts are thus compressed by the metal member.

25 In the enlarged view, Fig. 4, it will be seen that the fabric back (4) is clamped together with the parts (7), (9) and (10) under the turned over edge of the metal member (8), thus, adhesives are not entirely used in this construction to secure said back (4) to the cover.

30 For the smaller books, the adhesive used has proved of sufficient strength to secure the cover to the binding.

35 I have shown the cover as having nearly square corners, and in some cases where the leaves are provided with round corners it may prove desirable to form the cover with rounded corners of a 40 radius to suit such leaves.

45 The transparent cellulose outer facing (10), the decorative facing (11) and the under cover (9) are cemented together when the cover (6) of my book is formed with round corners to increase the smoothness of the corners, due to added distortion of the parts in forming when separate. The resilience and pliability of the paper in the parts (9) and (11) help to reduce the wrinkles 50 which form in the cellulose outer facing when not secured to said parts.

55 It may be seen that my invention may be modified in some of the details to suit particular uses, and I may wish to depart from the detailed con-

struction within the scope of the claims appended hereto, which succinctly set forth my invention.

I claim:

- 5 1. In a book, a cover comprising layers of material one of said layers being a metal member, the four edges of which are turned over clamping the other of said layers beneath its turned over edges, a fabric back turned under with the layers of material and thereby secured to said layers of material and to said metal member, and a transparent cellulose outer covering clamped under the turned over edges of the said metal member and completely covering it to protect the layers of material thereunder.
- 10 15 2. In a book, leaves, a flyleaf, a fabric back secured to said leaves and flyleaf, and a cover comprising a metal member and a plurality of parts in layers including said metal member, all of said edges of which are turned over the other parts and said fabric back being clamped under

the turned over edges of said metal member and secured to said flyleaf and fabric back, thereby firmly securing the cover to the other parts of the book, all of the layers including the metal member being bent back tightly to compress the softer parts between the turned over edges of the metal member and the body thereof.

- 15 20 3. In a book, a cover comprising layers of material, the outermost layers being substantially of greater length and width than the inner layers and a metal member substantially of less width and length than the outermost layers which are folded over the edges of said metal member and further folded with said metal member, all of said layers together being folded back upon themselves clamping said outermost layers between the turned over edges of the metal and body of the metal whereby said metal member is completely covered by said outer layer.

JOHN V. CAVALERO. 20
